CLAIM

The ornamental design for a luggage harness, as shown and described.

DESCRIPTION

FIG. 1 is a top, front right perspective view of the luggage harness showing my design;

FIG. 2 is a front view thereof;

FIG. 3 is a back view thereof;

FIG. 4 is a left view thereof;

FIG. 5 is a right view thereof;

FIG. 6 is a top plan view thereof; and,

FIG. 7 is a bottom plan view thereof.

The broken lines represent portions of the luggage harness that form no part of the claimed design.
